Dec. 1246

Wm. W. Stevens of Portland, Me.
Assignor to A. P. Richardson & Co, of same place.
Letters Patent No. 1246 dated May 15, 1860,

The schedule referred to in these Letters Patent and making part of the same.

Dec 1246

To all whom it may concern.

Be it known that I, William W. Stevens, of the City of Portland County of Cumberland and State of Maine, have invented a new and ornamental design for a Parlor Stoves (Which I term "The Arctic"), and I do hereby declare that the following is a full and exact description of the same, reference being had to the accompanying drawings and to the letters of reference thereon:

Of the said drawings-

Figure 3. represents a horizontal section of the front B, front doors C.C. and K, and end door K.K. taken through the line H.I.

I claim the configurations and ornaments above described and shown in the drawings as a design for a Parlor Stove.

In testimony whereof, I have hereunto set my hand and Seal this third day of April A. D. 1860.
